UNITED STATES PATENT OFFICE

2,544,662

HANDKERCHIEF IRONING MACHINE

Edwin E. Foster, Austin, Tex.

Application August 24, 1943, Serial No. 499,844

14 Claims. (Cl. 38—22)

1

This invention relates to a handkerchief and the like ironing machine of the type having movable bed members and a stationary head member with a mechanical means for applying ironing pressure.

It is an object of the invention to provide a handkerchief machine having two movable bed members and one stationary head member in which the total floor space occupied by the machine is about one-fourth that occupied by the ordinary turntable type of handkerchief machine. A further object is to provide means to shift the bed members from the loading position to the pressing position against the stationary head member. Another object of the invention is to provide a completely enclosed machine with all moving parts protected against possible contact with the operator, thereby eliminating the possibility of accidents, due to exposed moving parts, such as are present in the turntable type of machines.

In the ironing machine of the invention, an ironing pressure of about 2000 pounds or more is provided without the use of outside power other than a small amount of power which is replaced by the operator upon each ironing operation to thus take care of frictional losses. The pressure applying mechanism follows the principle of a bouncing ball in which the ball is held at the bottom of the bounce and later released with an additional boost. The travel of the ball through its up and down stroke is geared to operating links which shift the movable bed members.

It is thus a still further object of the invention to provide an ironing machine with a force applying means by what is termed the bouncing ball principle in which the operating functions of the machine are carried out at approximately the points where the ball reverses its travel or path of movement.

Other objects will be apparent from the following description when considered in connection with the accompanying drawings, in which:

Figure 1 is a front elevation of the machine,

Fig. 2 is a side elevation of the machine with the cover removed showing one bed member in the ironing position and the other in the loading position,

Fig. 3 is a view similar to Fig. 2 with the parts in another position,

Fig. 4 is a front elevation with the covers in section showing the parts in the position corresponding to Fig. 2,

Fig. 5 is a front elevation with the side covers in section showing the parts in the position corresponding to Fig. 3,

2

Fig. 6 is a perspective view of one of the bed members,

Fig. 7 is a perspective view of a part of the frame and head member.

Fig. 8 is a view similar to Figs. 2 and 3 showing a half-way position of the parts from the position of Fig. 3 to Fig. 2,

Fig. 9 is a view similar to Figs. 2 and 3 showing a half-way position of the parts from the position of Fig. 2 to Fig. 3, and

Fig. 10 is a sectional view of the details of a bed member and a latch member taken on line 10—10 of Fig. 2.

The handkerchief ironing machine is provided with a rectangular base frame 40 and two side frame members 41. Suitable covers or closure panels 43 are provided to protect the various parts of the mechanism.

The head member 3, which is suitably heated, is securely mounted in the frame members 41 at the top and back of the machine. Two movable bed members 1 and 2 are provided for the machine each having a rectangular shape with a pair of oppositely directed pins 35 and a square block or bearing 26 on the end of each pin. A pair of thumb buttons or levers 4 and 5, one on each side of the machine, are pivotally mounted at 70 at the front side of the machine and each of which is connected to a rod 44 which are in turn connected to a small bell crank lever 6. This bell-crank lever 6 functions as a safety latch for a foot pedal 7 pivoted at 8 and connected to a three-armed lever 9. One arm 45 of the lever 9 has a latch member 11 pivoted thereto at 15 and having a roller 13 and an arm 46. A tension spring 47 is secured at one end to the arm 46 and the other end to the frame of the machine. The latch 11 has a hook portion 48 which cooperates and grips a roller 16 secured to a weight 17 of any suitable shape and weight but is shown as a cylinder. A resilient restraining member 72 connected at one end to the lever 9 and the other end to the latch 11 maintains the latter in position to receive the roller 16.

The weight 17 is secured to one end of a tapered leaf spring 12, the other end of this spring being secured to a shaft 18 which latter is rotatably mounted in lugs or bearings 49 secured to the frame. A short lever 19, Fig. 4, is pinned or secured on each end of the shaft 18 and an extended link 20 is pivotally secured to each lever 19 at one end thereof. The other end of each link 20 is pivotally connected at 71 to a raising arm 21 for the bed members 1 and 2 and these arms 21 are pivoted at 22 to the frame of the machine.

Each arm 21 is provided with a latch finger

50 pivotally mounted at 51 and held in position by a cantilever spring 52 which is fixed at one end 53 to the arm 21 and the other or free end rides between two guide pins 54 on the latch 50. The spring 52 functions to maintain the finger 50 in line to grip the successive bed members 1 and 2.

Another pair of levers 23 are pinned or secured on the shaft 18 and to each of these levers a link 24 is pivotally mounted at one end thereof, the other end of each link 24 being pivotally secured to an arm or lug 55 secured to or forming a part of a lifting arm 25, Fig. 4. Each lifting arm 25 is provided with a semi-circular portion 56, the purpose of which will be explained when describing the operation of the machine.

Each bed member 1, 2, Fig. 6, is composed of a base plate 57 of metal or other suitable material with a pad or cover 58 on which the handkerchiefs to be ironed are placed. The pair of pins 35 are secured at opposite axial points on the base plate 57 and each pin is provided with the square guide block 26. Each block 26 slides in a guide track 27 provided in the frame 41.

A post 59 is secured to the frame on the base thereof. A wedge member 28 is supported on one end of a lever 32 pivoted at 33 to the front plate 60 of the machine, Fig. 2. The wedge member 28 is adjacent the post 59 and has a friction lining 29 which slides on a surface 30 on the post 59. The wedge 28 is vertically movable by the lever 32 by means of a bolt 61. The wedge 28 is lifted by means of a roller 31 suitably mounted on the shaft 18 which contacts the lever 32. As shown in Fig. 3 the roller 31 contacts the lever 32 and lifts the latter which causes the wedge 28 to rise relative to the guide post 59 and surface 30.

The post 59 is suitably made integral with a plate 14 which acts as a base member on which the roller 13 may contact.

The roller 31 may be secured or mounted on the shaft 18 in any desired manner such as lugs or other elements.

A third arm 62 of the bell crank lever 9 contacts and cooperates with the wedge 28 by means of a roller 75 as will be explained in the operation of the machine.

A latch 34 is provided on each side of the machine to prevent the bed member 1 when it has just been moved into its longitudinal position from rebounding when the arm 25 is moved from engagement therewith.

The front plate or cover 60 is provided with a section 36 which is hinged at 37 and provided with a spring 38. This is a safety device to prevent the operator's hand from being injured in case it should be accidentally in the path of a returning bed member. A bar or bumper member 39 may be provided as a stop for the lifting arm 25.

The machine operates as follows:

The operator spreads the handkerchief upon the horizontal bed member 1, Fig. 2, while the vertical bed member 2 is pressing, or ironing a second handkerchief against the vertical head member 3. In order to change the relative positions of the bed members 1 and 2, the operator presses down on the thumb buttons 4 and 5, which actuates the levers 6 and then steps lightly on the toe-pedal 7. When both buttons 4 and 5 are pushed, which are so interconnected that both must be pushed, rod 44 lifts up to rotate bell crank lever 6, Fig. 2, counterclockwise to remove it from under a roller secured on the pedal 7. As

the pedal 7 moves downward, pivoting counterclockwise about the point 8, the lever 9 pivots clockwise about the pivot point 10, causing the latch member 11 to further load the tapered leaf spring 12 by forcing or pulling the weight 17 slightly downward. Near the lower end of the pedal stroke, the roller 13 on the lower end of the latch 11 contacts the plate 14, which moves the lever 11 clockwise about the pivot-point 15 on the lever 9, thereby releasing the latch member 11 from the roller 16, which is attached to the weight 17. As the latch 11 is released the weight 17 leaps upward due to the stored-up energy in the spring 12 and rotates the shaft 18 with it. As the ball reaches its extreme upward position, the parts assume the position shown in Fig. 3. As the ball 17 leaps upward and returns, the arms 25 reach down and lift the bed member 2 to the new position. The bed member 1 stops against the vertical head member and the ironing pressure is applied through a mechanical advantage and the momentum in the ball 17 is absorbed in the spring 12 as the latch 11 catches the ball 17 at the extreme lower position of the bounce. Immediately after the ball 17 is released and the leaf spring 12 kicks it upward, the pressure against the arm 21 is released from the vertical bed member 2 and this bed member falls downward guided by the square blocks 26 in the slot 27. By the time the block 26 reaches the lower end of the slot 27, the arms 25 are in place to absorb the kinetic energy of the falling weight of the bed member. This energy is temporarily stored in the weight 17 and spring 12, to be used later in lifting the bed member to the horizontal position. The mechanism 11 used for grabbing the weight 17 at the extreme lower limit of its travel is, in effect, an over-running clutch latch 11, its purpose being to engage the latch and move therewith without absorbing any of the energy in the weight and lock the weight in its extreme position thereby holding all the energy in the spring 12 for future use. In order to replace the mechanical and air friction losses, the pedal 7 is provided to operate lever 9 for further compressing the spring 12 before releasing the latch 11, as previously described. An overrunning clutch latch is disclosed in my prior Patent No. 2,476,363 issued July 19, 1949.

Fig. 8 shows the movable bed members at the time they are in a half-way position, going from the position shown in Fig. 3 to that shown in Fig. 2. The arm 25 is provided with a recessed portion 56 to receive the round neck extending between the square block 26 and the bed member 2 itself. This recessed portion makes the square block follow the inside track of the curved guide tracks. When the arm 21 lowers to the position shown in Fig. 3, the latch member 50 pivots outward over the square block 26 and snaps back into position due to the spring 52, in order that it may lift the bed member by hook contact 73 under the bottom edge of the square block 26.

Fig. 9 shows the parts in the half-way position between Fig. 2 and Fig. 3. It is noted that by the time the vertical bed member 2 falls to its lower position the arm 25 has moved into place to catch the round neck of the falling bed member on each side. The weight of the falling bed member upon the arm 25 will tend to accelerate the weight 17, thereby storing this energy to be used on the lifting stroke of the same bed member.

The latches on the arms 21 contact the lower edge of the square blocks, but the lower arms 25 contact the round neck portion which supports the square blocks. During the time when the bed member is moving from its vertical position and back to the horizontal position, the pressed handkerchief will adhere to the padded bed member and will have to be forcibly "peeled off" by the operator before replacing it with a new handkerchief.

When the parts change from the position shown in Fig. 3 to that shown in Fig. 2, passing through the intermediate positions shown in Fig. 8, the bed members move with accelerated speed. The horizontal bed member carries the handkerchief directly against the stationary head member with an impact and is latched in that position, that is, at the point of highest pressure, and this pressure is maintained, due to the fact that the ball 17 is latched in its extreme lower position and the leaf spring 12 is held in its loaded position. When the ball 17 is released by means of the latch 11, the parts move from the position shown in Fig. 2 to the position shown in Fig. 3 through the intermediate position shown in Fig. 9, with a decelerated speed, just as a ball would move when going from the bottom to the top of its bounce. Of course, the mass of the weight 17 and the strength of the spring 12 can be used to control the speed of these changes. One of the advantages of this system is that the changes will occur faster than could be tolerated in an exposed turn table type handkerchief machine.

In Fig. 2 the ironing force is being exerted through the leaf spring 12, which forces the shaft 18 clockwise, causing a compression in the link 20, thereby forcing the arm 21 in a clockwise position about the point 22 and the latch 50 against the square block 26. Since it is not desired to exert a corresponding force through the arms 25, these arms 25 can be made flexible. The resulting rebound, due to such flexible arms 25, will return the energy absorbed by them. The latch 34 which is spring pressed by means of spring 74 is provided on each side of the machine to keep the horizontal bed member from rebounding when the arm 25 is moved away from the rounded neck portion 35. In Fig. 3 as the ball 17 and spring 12 move down or to the right wedge 28 is held in its lifted position by spring 47 which tends to rotate lever 9 counter-clockwise. As shown in Fig. 2 when the ball 17 engages the latch 11 the momentum forces the lever 9 clockwise, thus moving the arm 62 to the right and permitting the wedge 28 to fall until it again engages or is stopped by contact with the arm 62. In this position the ball 17 has reached the extreme bottom position and is latched at that position and the spring 12 is applying ironing pressure. After the ironing operation has been completed and upon release by stepping on pedal 7, lever 9 rotates clockwise to further load or charge the spring 12 and finally the spring and ball are released by latch 11, so that on the up movement, Fig. 8, roller 31 engages lever 32 to raise the latter and thereby the wedge 28 to the position of Fig. 3.

It is to be understood that the bouncing ball or swinging pendulum feature of this invention is not limited to the specific type of machine herein-illustrated and described but it may be used in any force applying machine of any type.

I claim as my invention:

1. An ironing machine particularly for handkerchiefs and the like comprising a frame, a

stationary head member secured on the frame, a bed member movably mounted in said frame, means on the frame for moving and guiding said bed member from a position for removing an ironed handkerchief and placing a new handkerchief to be ironed to a position in contact with the head member to iron the handkerchief, and a leaf spring with a weight at one end movably mounted in the frame at the other end and connected and operated to furnish the ironing force when the head and bed members are in contact with each other, and a latch pivotally mounted in the frame operable to contact and hold the weight in the force applying position during the ironing operation.

2. An ironing machine particularly for handkerchiefs and the like comprising a frame, a stationary head member secured on the frame, a bed member movably mounted in said frame, means on the frame for moving and guiding said bed member from a position for removing an ironed handkerchief and placing a new handkerchief to be ironed to a position in contact with the head member to iron the handkerchief, a leaf spring with a weight at one end movably mounted in the frame at the other end and connected and operated to furnish the ironing force when the head and bed members are in contact with each other, and means for holding the weight in the force applying position during the ironing operation.

3. An ironing machine particularly for handkerchiefs and the like, comprising a frame having guide tracks therein, a stationary head member secured on the frame, a pair of bed members movable in said guide tracks, means operable in the frame for lifting said bed members from a loading position to an ironing position against the head member, means operable in the frame for receiving a released bed member after its ironing operation and returning it to the loading position after the other bed member has been lifted to its ironing position against the head member, and means for applying an ironing force on the bed member as each bed member contacts the head member, said last mentioned means including a leaf spring secured at one end in the frame and having a weight at the other end to operate as a spring board to apply the ironing pressure.

4. An ironing machine particularly for handkerchiefs and the like, comprising a frame having guide tracks therein, a stationary head member secured on the frame, a pair of bed members movable in said guide tracks, means operable in the frame for lifting said bed members from a loading position to an ironing position against the head member, means operable in the frame for receiving a released bed member after its ironing operation and returning it to the loading position after the other bed member has been lifted to its ironing position against the head member, means for applying an ironing force on the bed member as each bed member contacts the head member, said means including a weight mounted on one end of a leaf spring in the frame and functioning as a spring board to apply the ironing pressure, and a clutch latch operable in the frame for holding the weight in its pressure applying position.

5. An ironing machine particularly for handkerchiefs and the like, comprising a frame having guide tracks therein, a stationary head member secured on the frame, a pair of bed members movable in said guide tracks, means operable in the frame for lifting said bed members from a

loading position to an ironing position against the head member, means operable in the frame for receiving a released bed member after its ironing operation and returning it to the loading position after the other bed member has been lifted to its ironing position against the head member, means for applying an ironing force on the bed member as each bed member contacts the head member, said means including a weight mounted on one end of a leaf spring in the frame and functioning as a spring board to apply the ironing pressure, a clutch latch operable in the frame for holding the weight in its pressure applying position, and a foot pedal controlled device in the frame to release the latch.

6. An ironing machine particularly for handkerchiefs and the like, comprising a frame having guide tracks therein, a stationary head member secured on the frame, a pair of bed members movable in said guide tracks, means for lifting said bed members from a loading position to an ironing position against the head member, means for receiving a released bed member after its ironing operation and returning it to the loading position after the other bed member has been lifted to its ironing position against the head member, means for applying an ironing force on the bed member as each bed member contacts the head member, said means including a weight mounted on one end of a leaf spring and functioning as a spring board to apply the ironing pressure, a latch for holding the weight in its pressure applying position, means for movably mounting the latch to follow the downward movement of the weight, and clutch means adapted to secure both said latch and weight in their extreme lower positions.

7. An ironing machine according to claim 5, in which means are provided to releasably lock the pedal against release of the weight.

8. An ironing machine particularly for handkerchiefs and the like comprising a frame, a pair of relatively movable head and bed members in the frame, means operable in the frame for moving and guiding one of the members from a position for removing an ironed handkerchief and placing a new handkerchief to be ironed to a position in contact with the other member to iron the handkerchief, and a spring secured at one end in the frame and having a weight at the other end to provide the ironing force when the head and bed members are in contact with each other, and a latch member secured to the frame to hold the weight in the ironing force exerting position of the spring until the ironing step is completed and the weight released.

9. An ironing machine particularly for handkerchiefs and the like, comprising a frame having guide tracks therein, a stationary head member secured on the frame, a pair of bed members movable in said guide tracks, means for lifting said bed members from a loading position to an ironing position against the head member, means for receiving a released bed member after its ironing operation and returning it to the loading position after the other bed member has been lifted to its ironing position against the head member, means for applying an ironing force on the bed member as each bed member contacts the head member, said means including a weight mounted on one end of a leaf spring and functioning as a spring board to apply the ironing pressure, a shaft secured in the frame on which the leaf spring is rotatably mounted, means connected to the shaft and the lifting means and

receiving means to simultaneously operate the lifting and receiving means, and a latch device mounted to retain and hold the weight in the position in which the leaf spring is flexed and applies the ironing pressure between the head and bed members until released.

10. An ironing machine particularly for handkerchiefs and the like, comprising a frame having guide tracks therein, a stationary head member secured on the frame, a pair of bed members movable in said guide tracks, means for lifting said bed members from a loading position to an ironing position against the head member, means for receiving a released bed member after its ironing operation and returning it to the loading position after the other bed member has been lifted to its ironing position against the head member, means for applying an ironing force on the bed member as each bed member contacts the head member, said means including a weight mounted on one end of a leaf spring and functioning as a spring board to apply the ironing pressure, a shaft secured in the frame on which the leaf spring is rotatably mounted, means connected to the shaft and the lifting means and receiving means to simultaneously operate the lifting and receiving means, and means operable in the frame for holding the weight in the pressure applied position between a bed member and the head member until released.

11. An ironing machine comprising a movable and a fixed garment pressing element, means to guide said movable element between a loading position and a pressing position in engagement with said fixed element, a leaf spring, means to support one end of said spring for a limited rotary movement, a weight secured to the other end of said spring, means to latch said spring in a flexed position, means to further flex said spring and then release said latch means so that said spring and weight will urge said spring supporting means to the opposite limit of its motion whereupon the spring will flex in the opposite direction and then return said weight and spring to its initial latched position, and means responsive to movement of said spring supporting means through a complete cycle to move said movable pressing element from one of said positions to the other.

12. An ironing machine comprising a movable and a fixed garment pressing element, means to guide said movable element between a loading position and a pressing position in engagement with said fixed element, a leaf spring, means to support one end of said spring for a limited rotary movement, a weight secured to the other end of said spring, means to latch said spring in a flexed position, and means connected to the support means for the first mentioned end of the spring and to the movable element at the pressing position to utilize the force of the flexed spring for the ironing pressure.

13. An ironing machine comprising a movable and a fixed garment pressing element, means to guide said movable element between a loading position and a pressing position in engagement with said fixed element, a leaf spring, means to support one end of said spring for a limited rotary movement, a weight secured to the other end of said spring, means to latch said spring in a flexed position, means to engage the movable element to carry the latter from the loading position to the pressing position, and means connected to the support means for the first mentioned end of the spring and to the means to engage the mov-

able element to convey the force of the flexed spring to the movable element for the ironing pressure.

14. An ironing machine comprising a movable and a fixed garment pressing element, means to guide said movable element between a loading position and a pressing position in engagement with said fixed element, a leaf spring, means to support one end of said spring for a limited rotary movement, a weight secured to the other end of said spring, means to latch said spring in a flexed position, means to engage the movable element to carry the latter from the loading position to the pressing position, means connected to the support means for the first mentioned end of the spring and to the means to engage the movable element to convey the force of the flexed spring to the movable element for the ironing pressure, and means connected to the support means for the spring to carry the movable element back to the loading position.
